CENTRALIZER FOR DRILL STEELS

George H. Fuehrer, Phillipsburg, N. J., assignor
to Ingersoll-Rand Company, Jersey City, N. J.,
a corporation of New Jersey

Application May 21, 1938, Serial No. 209,162

4 Claims. (Cl. 255—45)

This invention relates to rock drills, and more particularly to a centralizer for a drill steel actuated by a rock drill of the reciprocatory type.

In many drilling operations it is difficult to 5 maintain the cutting end of a drill steel in coaxial alignment with the rock drill during the starting of a drill hole. This is more particularly true when the rock drill lies in an inclined or horizontal position. Under such conditions the cutting 10 end of a rapidly rotating drill steel whips or describes a gyratory movement which makes it difficult to start the drill hole correctly.

This erratic action of the drill steel is partly due to its inherent flexibility and in part to the 15 natural clearances between the drill steel and the chuck mechanism of the rock drill into which it extends. In drilling mechanisms in which chuck parts form the only support for the drill steel, and particularly when these chuck parts 20 become worn, the drill steel declines from the desired course of the drill hole and thereby speedily develops a condition in which the action of the rotation mechanism of the rock drill is hampered seriously.

25 These unfavorable conditions often continue undetected until the drill hole has been drilled to a considerable depth. If then the position of the rock drill is not changed to coincide with the course of the hole, as drilled, the drill steel will 30 bind in the work, thereby causing excessive wear on the gaging surfaces of the cutting bit. Obviously, this will lower the drilling efficiency of the apparatus and add materially to the cost of maintenance since it necessitates the frequent 35 reconditioning of the drill steel.

It is accordingly an object of the present invention to stabilize the overhanging portion of the drill steel and thereby maintain the cutting bit in axial alignment with the rock drill actuating 40 the drill steel.

Another object is to enable the centralizer to be conveniently moved into the guiding and non-guiding positions.

45 Other objects will be in part obvious and in part pointed out hereinafter.

In the drawing accompanying this specification and in which similar reference numerals refer to similar parts:

50 Figure 1 is a longitudinal side elevation of rock drilling apparatus equipped with a centralizer constructed in accordance with the practice of the invention.

Figure 2 is an end elevation of the centralizer 55 and the rock drill taken through Figure 1 on the

line 2—2 and showing the guide elements of the centralizer in non-guiding position.

Figure 3 is an elevation, partly in section, taken through Figure 1 on the line 3—3.

Figure 4 is a transverse view taken through 5 Figure 3 on the line 4—4 looking in the direction indicated by the arrows, and

Figure 5 is a similar view taken through Figure 2 on the line 5—5.

Referring more particularly to the drawing, 10 20 and 21 designate the front ends of a rock drill and a shell, respectively, and 22 a drill steel, the shank of which may extend into the front end of the rock drill 20 to receive the blows of a hammer piston (not shown). The opposite or free end of 15 the drill steel 22 constitutes the cutting bit 23 for drilling holes into rock 24.

The rock drill 20 and the shell 21 are of the type that are usually provided with interlocking guiding elements (not shown) to enable the 20 rock drill to be advanced toward the work in accordance with the penetration of the drill steel 22 thereinto.

The centralizer, constructed in accordance with the practice of the invention and designated in 25 its entirety by 25, is attached to the front end of the shell 21. It comprises a support 26 having a flange 27 which seats against and is clamped to the front end of the shell 21 by bolts 28. On the opposite end of the support 26 are a pair of 30 trunnions 29 which serve as pivots for guide arms 30 serving to maintain the drill steel 22 in axial alignment with the rock drill 20.

The trunnions 29 are inclined with respect to the longitudinal axis of the support 26 and arranged angularly with respect to each other. They may, as shown, be integral parts of the support or formed as separate members and suitably attached to the support.

The guide arms 30 are seated loosely upon the 40 trunnions 29 whereon they rotate, and to this end are provided with cup-shaped hubs 31 having sockets 32 to receive the trunnions 29. Preferably, the trunnions 29 are of somewhat less length than the depth of the sockets 32 and seating surfaces 33 are provided at the bases of the trunnions for the hubs 31.

As a preferred form of construction the guide arms 30 are located at the outer or closed ends of the hub 31. These guide arms may be slightly 50 bowed, as illustrated, and terminate in heads 34 having partly cylindrical recesses 35 in their opposed surfaces to receive the drill steel 22. Sufficient clearance is provided between the recesses 35 and the body portion of the drill steel 55

to allow the latter to rotate freely within the recesses.

Suitable means are provided to prevent end-wise movement of the hubs 31 with respect to the trunnions 29 and also to maintain the guide arms in the various positions which they will occupy in practice. To this end the portions of the hub 31 adjacent the seating surfaces 33 are provided with flanges 36 having on their upper ends seating surfaces, three in the present instance, designated 37, 38 and 39 which are inclined with respect to the axes of the hub 31.

The degree of inclination of the seating surfaces is the same as that of the trunnions with respect to the axis of the support. Thus, when the guide arms occupy a position in which they engage the drill steel the seating surface 37 will lie in a horizontal plane and provide a seat for a clamping member or plate 40 whereby the guide arms are retained on the trunnions.

Likewise, the surfaces, either 38 or 39, depending upon whether a given guide arm occupies the right or the left hand trunnion, will lie in the horizontal plane in the non-guiding positions of the guide arms shown in Figure 2 to provide a seat for the plate 40.

In this connection it may be pointed out that only one seating surface 38 or 39 is utilized in the non-guiding positions of the guide arms but two surfaces are provided in order to enable the guide arms to be interchanged and also to avoid the waste of time that is often occasioned in determining whether the guide arms are correctly assembled on the support.

For a like reason the plate 40 is provided at its ends with two prongs 41 which lie on opposite sides of the hub 31, although in practice only one prong actually engages one seating surface on each arm. By providing two prongs at each end of the plate all chance of placing the plate in an incorrect position are eliminated. The prongs also assure maximum areas of contact between the plate 40 and the seating surfaces to avoid vibratory movement of the guide arms with respect to the trunnions and, therefore, wear on the cooperating surfaces of these elements.

The element serving to press the plate 40 against the seating surfaces on the flanges 36 consists, in the present instance, of a spring 42 inserted in a recess in the lower surface of the support 26. The spring 42 encircles a bolt 43 having a head 44 which serves as a seat for an end of the spring. The bolt extends through the support 26 and the plate 40 and has a nut 45 threaded on its upper end for adjusting the spring 42. Preferably, a round faced washer 46 is interposed between the nut 45 and the plate 40 and seats into a concave recess 47 in the plate 40 to enable the plate 40 to adjust itself readily with respect to the seating surfaces on the guide arms.

In the operation of the device, whenever it is desired to start a new drill hole, the arms 25 are rocked to the guiding positions in which the drill steel 22 lies in the recesses 35. In this position of the guide arms the clamping plate 40 will seat upon the surfaces 37 and will hold the guide arms immovable.

The arms remain in the guiding position during the ensuing drilling operation and when the rock drill advances into contact with the portions 10 of the arms encircling the drill steel said arms will be rocked out of the guiding position into a non-guiding position in which the surface 38 of one arm and a surface 39 of the other arm will lie beneath the plate 40. The drill may thereafter 15 continue operation and its advancing movement until the working implement has penetrated the rock to the limit of its extent. After the rock drill 20 has been retracted on the shell 21 and a new drill steel of greater length placed therein 20 the guide arms 25 are again, rocked to the guiding position shown in Figures 1 and 3 to support the drill steel.

I claim:

1. A centralizer for drill steels, comprising a support, a pair of guide arms, pivots on the support for the guide arms arranged angularly with respect to each other, a spring-pressed member on the support for retaining the guide arms on the pivots, and means on the guide arms engaging the spring-pressed member for holding the guide arms in guiding and non-guiding positions.

2. A centralizer for drill steels, comprising a support, a pair of guide arms, pivots on the supports for the guide arms arranged angularly with respect to each other, a plurality of seating surfaces on the guide arms, and a spring-pressed member on the support to engage the seating surfaces for holding the guide arms in guiding and non-guiding positions.

3. A centralizer for drill steels, comprising a support, a pair of guide arms, hubs on the guide arms having sockets, pivots on the support extending into the sockets and being arranged angularly with respect to each other, flanges on 45 the hubs each having a plurality of seating surfaces, and a spring-pressed plate on the support to engage the seating surfaces for retaining the guide arms on the pivots and holding the guide arms in guiding and non-guiding positions.

4. A centralizer for drill steels, comprising a support, a pair of guide arms, pivots on the support for the guide arms, hubs on the guide arms having sockets to receive the pivots, a plurality of seating surfaces on the hubs inclined with 55 respect to the axes of the hubs and with respect to each other, and spring-pressed means on the support to engage the seating surfaces for retaining the guide arms on the pivots and for holding the guide arms in guiding and non- 60 guiding positions.

GEORGE H. FUEHRER.
